Richard Oliver.

UNITED STATES PATENT OFFICE.

PETER PECORARO, OF BROOKLYN, NEW YORK.

DESIGN FOR A COMBINATION TRAY.

60,424.

Specification for Design.

Patented Feb. 14, 1922.

Application filed June 1, 1921. Serial No. 474,270. Term of patent 3½ years.

To all whom it may concern:

Be it known that I, PETER PECORARO, a citizen of the United States, residing at Brooklyn, in the county of Kings and State of New York, have invented a new, original, and ornamental Design for a Combination Tray, of which the following is a specification.

In the accompanying drawings:

Figure 1 is a view in top plan of my design for a combination tray, and

Figure 2 is a view thereof in longitudinal section.

The design consists of a plurality of depressions formed in the bottom of a tray,

said depressions being arranged in a symmetrical manner and conforming in shape and size to various articles of a set of dishes, so that said articles may rest in said depressions, some depressions resembling articles of silver table ware, substantially as shown.

I claim—

The ornamental design for a combination tray, as shown and described.

In testimony whereof I affix my signature in presence of a witness.

PETER PECORARO. [L.S.]

Witness:

W.M. ZEAMAN.
